UNITED STATES PATENT OFFICE.

GILLES HOLST AND EKKO OOSTERHUIS, OF EINDHOVEN, NETHERLANDS, ASSIGNEES
TO NAAMLOOZE VENNOOTSCHAP PHILIPS' GLOEILAMPEN-FABRIEKEN, OF EINDHOVEN, NETHERLANDS.

ELECTRON-DISCHARGE DEVICE.

Application filed November 4, 1921. Serial No. 512,889.

To all whom it may concern:

Be it known that we, GILLES HOLST and EKKO OOSTERHUIS, subjects of the Queen of the Netherlands, residing at Eindhoven, in the Province of North-Brabant, in the Kingdom of the Netherlands, have invented certain new and useful Improvements in an Electron-Discharge Device, of which the following is a specification.

10 The invention relates to an improvement on the present type of gas-filled electron discharge devices and more particularly it relates to electron discharge devices comprising an incandescent cathode, an anode, a 15 grid, and a filling of gas, such as are used in wireless telegraphy or telephony, and which are generally known as "soft valves."

The object of the invention is to provide a gas-filled electron discharge device which 20 may comprise a glass vessel containing an incandescent cathode, an anode and a grid interposed between the anode and the cathode and with a gas-filling of such nature and pressure that the device operates with 25 reduced anode tension and is practically constant in its operation.

Attention has been drawn in technical literature to the fact, that gas-filled ionic valves show some advantages above ionic 30 valves having a high vacuum. The most important advantage is the low tension at the anode, necessary for a maximum strength of signal and the fact that when using gas-filled ionic valves, a grid leak between the grid electrode and the incandescent filament becomes superfluous.

An inconvenience which occurs with gas-filled valves is their lack of uniform action, which is due to the alteration of pressure of 40 the gas-filling in consequence of the disappearance of gases and the emanation of new gases during the operation of the valve.

The improvement according to this invention consists in the glass bulb of the valve being exclusively filled with pure argon of low pressure. By a preliminary heating of the valve the glass and metal parts therein are freed from the greater part of the absorbed gases.

Applicants have found, that the argon at 50 a pressure below $\frac{1}{10}$ mm. of mercury works quite uniformly, so that after operating for about 1000 hours the properties are unaltered.

It has also been experienced that in order to avoid glow discharge and deleterious disintegration of the cathode, the pressure of the argon-filling must be reduced beneath a certain limit, practically beneath a pressure of $\frac{1}{10}$ mm. mercury.

In the accompanying drawing a form of electron discharge device has been illustrated on which the invention may be incorporated.

As shown in the drawing the device comprises a receptacle 5 having enclosed therein a filament or cathode 1, an anode 3 and a grid 2, whereas the necessary contacts may be closed by means of the metal-fitting 5.

The inner space 6 of the receptacle is carefully evacuated, suitable steps being performed to expel all gases from the glass and from the electrodes e. g. by heating them up to a suitable temperature. The receptacle 5 is thus first evacuated as it were 70 to have a permanent high vacuum, and the method described in the British Patent No. 15,788, A. D. 1914, may be adopted to accomplish this purpose.

After this the space 6 is exclusively filled 80 with pure argon of a pressure not exceeding the upper-limit of $\frac{1}{10}$ mm. of mercury.

A thus treated device operates at an anode tension of 25-30 volts whereas in the heretofore employed high vacuum tubes said tension amounts to 35-100 volts.

In practice we have found that a very constant operation is obtained with a pressure of the argon of about $\frac{1}{10}$ mm. mercury; however a good result may also be obtained 90 with slightly different pressures of the argon, as the proper pressure slightly varies with the current density on the electrodes. However this pressure should not exceed a pressure of $\frac{1}{10}$ mm. of mercury.

Furthermore we wish to be understood 95 that while we have shown and described a single structure in which our invention is ap-

plied, many changes may be made in the structure of the apparatus, without departing from the scope of our invention.

What we claim is:

1. An electric discharge tube comprising an incandescent cathode, an anode, and a grid, and a gass filling consisting exclusively of pure argon of a pressure not exceeding $\frac{1}{16}$ mm. of mercury.

2. An electric discharge tube comprising 10 an incandescent cathode, an anode, and a grid, and a gass filling consisting exclusively of pure argon of a pressure between $\frac{1}{160}$ and $\frac{1}{20}$ mm. of mercury.

In testimony whereof we affix our signatures.

GILLES HOLST.
EKKO OOSTERHUIS.
